UNITED STATES PATENT OFFICE.

THEOPHILE SCHWAB LOEILLET, OF GENEVA, SWITZERLAND.

DESIGN FOR A WATCHCASE.

Application filed June 2, 1924. Serial No. 9,781. Term of patent 14 years.

To all whom it may concern:

Be it known that I, THEOPHILE SCHWAB LOEILLET, a citizen of Switzerland, residing at Rue du Mont Blanc 22, Geneva, Switzerland, have invented a new, original, and ornamental Design for a Watchcase, of which the following is a specification, reference being had to the accompanying drawing, forming part thereof.

In the drawing Fig. 1 represents in perspective view the front side of the watch case and Fig. 2 the back side.

I claim:

The ornamental design for a watch case, as shown.

THEOPHILE SCHWAB LOEILLET.
